(57) **CLAIM**

I claim the ornamental design for a multi-colored, automotive vehicle wheel, as shown and described.

DESCRIPTION

FIG. 1 is a top perspective view showing a multi-colored, automotive vehicle wheel of my new design; FIG. 2 is a side plan view thereof; FIG. 3 is a top plan view thereof; FIG. 4 is a rear plan view thereof; FIG. 5 is a bottom plan view thereof; FIG. 6 is a front plan view thereof; and, FIG. 7 is a side plan view thereof, opposite FIG. 2. The broken lines (for example the back side of the wheel) illustrate portions of the multi-colored, automotive vehicle wheel that form no part of the claimed design. The stippling indicates a contrast in appearance.
